UNITED STATES PATENT OFFICE.

JOHN H. LANE, OF DETROIT, MICHIGAN, ASSIGNOR TO PENINSULAR STOVE COMPANY, OF DETROIT, MICHIGAN, A CORPORATION OF MICHIGAN.

COMBINATION COAL AND GAS RANGE.

1,388,653.

Specification of Letters Patent. Patented Aug. 23, 1921.

Application filed September 16, 1918. Serial No. 254,174.

To all whom it may concern:

Be it known that I, JOHN H. LANE, a citizen of the United States of America, residing at Detroit, in the county of Wayne and State of Michigan, have invented certain new and useful Improvements in Combination Coal and Gas Ranges, of which the following is a specification, reference being had thereto to the accompanying drawings.

10 The invention relates to combination coal and gas stoves and has more particular reference to the construction of the gas burner and associated means by which the stove may be easily adjusted for use with either 15 fuel. To this end the invention consists in the construction as hereinafter set forth.

In the drawings:

Figure 1 is a section through a portion of the stove in the longitudinal plane of the 20 burner;

Fig. 2 is a section on line 2—2 of Fig. 1;

Fig. 3 is a similar section showing the parts in different adjustment;

Fig. 4 is an end elevation;

25 Fig. 5 is a perspective view showing the side of the stove at which the adjusting mechanism is located.

A is the oven having the bottom B with a flue C therebeneath, and D is an end wall of 30 the oven with the flue E between the same and the outer casing F. G is the gas burner which extends through the walls F and D into the oven space and when in position for use is slightly above the bottom B.

35 It is desirable to remove the burner from the oven when the stove is used with solid fuel and it is also necessary to vent the oven when the gas burner is used and to close the vent when coal is used. This I have accomplished first by rotatively mounting the burner eccentric to the axis of rotation and by forming a recess in the bottom of the oven in which the burner is located when not in use and from which it is lifted into 40 the oven by a rotational movement.

In detail H is a groove or depression in the oven bottom B which is substantially semi-circular in cross-section. I is a semi-circular portion of the burner G which on its convex 50 side is provided with the perforations J for the gas jets, while its flat side K is imperforate and adapted to form a complementary portion of the oven bottom. At the outer end of the semi-circular portion I the member G is of a full circular cross-section and

is formed with a shoulder L for bearing against the outer face of the wall D and a second shoulder M for bearing against the outer face of the wall F. Adjacent to this shoulder M is a groove N for receiving the 60 lower portion of the wall F surrounding the burner opening, while a removable semi-circular plate O engages the upper portion of this groove. Thus the burner extends through the flue E without leaving any 65 opening for the escape of gases. A portion P outside of the oven is provided with an air adjusting valve Q, while a gas nozzle R is inserted centrally through this valve to form a Bunsen burner of the usual construction. 70 The inner end of the member G has a pintle S which is alined with the axis of rotation and engages a suitable bearing on the opposite side wall of the oven.

With the construction as thus far described it will be evident that the burner may be rotated and in one position, shown in Fig. 2, the semi-circular portion I is in the depression H in the oven bottom, while a half revolution of the burner about its 80 axis will bring it into the position shown in Fig. 2. Here the gas jets J will clear the oven bottom but will be directed laterally from opposite sides of the burner.

For convenience in adjustment of the 85 burner, a gear ring T is mounted on its outer end and a gear segment U in mesh with this ring is pivoted at U'. The gear segment U is rotatively actuatable by a lever V, pivoted eccentrically thereto and extending to the 90 front of the stove through the shelf supporting bracket W, said lever also having an extension V' projecting rearwardly beyond the point of attachment to the gear segment U and operatively connected with a valve or 95 damper X controlling a vent through the rear wall of the oven. The arrangement is such that whenever the lever V is operated to adjust the burner to its upper position the valve therefor will be simultaneously opened 100 to vent the oven. On the other hand when the lever V is operated to lower the burner into the groove H the valve therefor will be closed.

For supplying additional air to the burner 105 I preferably arrange on the opposite end of the oven an air flue Y passing through the ash-pit section of the stove, and a valve or damper Z controlled by a handle Z' is employed for opening and closing this vent. 110

When the vent is open air is admitted into the channel H beneath the burner while in the position shown in Fig. 3, and the air thus admitted will be distributed throughout the 5 length of the burner and passing upward will be commingled with the gas jets J.

What I claim as my invention is:—

1. In a combination coal and gas stove, an inner casing forming an oven having a 10 grooved bottom and an aperture in alignment with said groove through its end wall, an outer casing spaced from said inner casing to form bottom and side flues, the side wall thereof having an aperture in 15 alignment with an aperture in the inner casing, and a burner extending through said aligned apertures having an eccentric portion lying in said groove in one position of adjustment and raised above the oven bottom 20 in another position of adjustment, and shoulders on said burner for coöperating with the inner and outer side walls to form a sealed joint.

2. In a combination coal and gas range, 25 an oven and an ash pit at one side thereof, said oven having its bottom formed with a groove extending transversely of the ash pit, an air duct within the ash pit communicating at its upper end with one end of said 30 groove and having an air inlet at its lower end, and a burner adjustable from a stored position within the groove to a position of use close adjacent the groove, the groove forming a duct, when the burner is adjusted 35 for use, to distribute air admitted through said opening to the burner.

3. In a combination coal and gas range, 40 an oven and an ash pit at one side thereof,

said oven having its bottom formed with a groove, an air duct within the ash pit communicating with said oven at its upper end and having an air inlet at its lower end, and a burner adjustable from a stored position within said groove to a position of use 45 close adjacent the groove, the latter forming a duct, when the burner is adjusted to use, to distribute air admitted through the air duct in the ash pit.

4. In a combination coal and gas range, 50 an oven provided with a semi-cylindrical groove in its bottom, and a semi-cylindrical burner rotatively adjustable through substantially 180° to shift said burner from a stored position within said groove to a position of use above the groove and substantially closing the groove.

5. In a combination coal and gas range, 55 a combination with an oven having a groove in the bottom thereof, of a burner rotatively adjustable through substantially 180° to shift said burner from a stored position within said groove to a position of use above the same, restrictive air outlets from the grooves being formed at each side of the burner in its position of use, and means for 60 delivering air to said groove.

6. In a combination gas and coal range, 65 the combination with an oven having a recess in the bottom thereof, of a burner rotatably mounted in said recess, having jet openings discharging into the oven in one position of rotation and having a surface flush with the oven bottom in the reverse position of the burner.

In testimony whereof I affix my signature. 75
JOHN H. LANE.
